UNITED STATES PATENT OFFICE

130,591

DESIGN FOR A COMBINATION POWDER BOX, MIRROR, AND PICTURE FRAME

Marianne Oesterreicher, New York, N. Y.

Application April 9, 1941, Serial No. 100,268

Term of patent 3½ years

To all whom it may concern:

Be it known that I, Marianne Oesterreicher, a citizen of the Kingdom of Albania and a resident of the city and State of New York, with a post-office address at the Mayflower Hotel, 61st Street and Central Park West, in the Borough of Manhattan, city and State of New York, have invented a new, original, and ornamental Design for a Combination Powder Box, Mirror, and Picture Frame, of which the following is a specification, reference being had to the accompanying drawing, forming part thereof, in which:

Figure 1 is a front perspective view of a combination powder box, mirror and picture frame embodying my new design with the box in open

position, showing the mirror side of the internal portion;

Figure 2 is a similar view thereof showing the picture frame side with the frame in a display position; and

Figure 3 is a perspective view thereof in closed position.

The dominant features of the design reside in the portions shown in full lines.

I claim:

The ornamental design for a combination powder box, mirror, and picture frame, as shown and described.

MARIANNE OESTERREICHER.
